The ornamental design for a terminal, as shown and described.

DESCRIPTION

FIG. 1 is a plan view of a terminal showing the new design; FIG. 2 is an underside view of the terminal of FIG. 1; FIG. 3 is a left side view of the terminal of FIG. 1; FIG. 4 is a right side view from the other side of the terminal of FIG. 1; FIG. 5 is an end view of the terminal of FIG. 1; FIG. 6 is an end view of the terminal showing the new design; and, FIG. 7 is a perspective view of the terminal showing the new design. The broken lines are shown for the purpose of illustrating portions of the article and form no part of the claimed design.
